UNITED STATES PATENT OFFICE.

JOSHUA D. HEMPHILL, OF CENTRAL FALLS, RHODE ISLAND.

AUTOMATIC CIRCULAR-KNITTING MACHINE.

935,981.

Specification of Letters Patent.

Patented Oct. 5, 1909.

Application filed May 22, 1908. Serial No. 434,283.

To all whom it may concern:

Be it known that I, JOSHUA D. HEMPHILL, a citizen of the United States of America, and a resident of Central Falls, in the county 5 of Providence and State of Rhode Island, have invented certain new and useful Improvements in Automatic Circular-Knitting Machines, of which the following is a specification.

10 This invention relates generally to automatic circular knitting-machines, an example of the latter being shown and described in my pending parent application, Serial No. 308,106, filed in the U. S. Patent 15 Office. In said application the needles and sinkers are mounted in and rotate bodily with the knitting-cylinder, while at the same time the cams, &c., for controlling the action of the needles and sinkers remain practically 20 stationary.

The present invention is well adapted to be employed in connection with a revoluble knitting-cylinder and a plurality of automatically controlled yarn-feeding devices 25 for placing one or more of the knitting yarns into and out of action at predetermined points during the knitting say of the stocking.

The invention herewith consists essentially 30 of means devised and arranged for receiving the temporarily inactive yarn or yarns and clamping or binding it in a relatively stationary position within the area of the cylinder's chamber or bore until the yarn is 35 again brought into the knitting position, the conjoint action of the cylinder and its needles then causing the yarn to be freed or released from the binding device and knitted into the fabric in a normal manner. It may 40 be added that the thus-clamped floating-yarn remains integral and is not parted or severed during the production of the stocking.

In knitting-machines as sometimes devised the temporarily inactive or floating yarns are guided to a relatively small continuously open eye-shaped space located at or near the center of the cylinder where they are free to move about laterally within the 45 limits of the circumscribed open space but still being connected to the work and bobbins under more or less tension. The yarn-feeding means is adapted to reintroduce the floating yarn, then supposedly being normally supported in the said open eye, from 50 the latter to the hooks of the needles at the

proper time or point in the knitting operation; but in practice, however, it frequently happens that the thus loosely held floating yarn becomes accidentally withdrawn from the eye or yarn-guide or even broken thus 60 producing imperfect work. It may be added that in some cases the continued revolution of the work or of the floating yarn causes the latter to twist or untwist to an abnormal 65 degree (according to the direction of rotation) and thus sever the yarn; sometimes the added twist to the yarn produces "kinks", which are liable to break the needles when, the yarn is brought into knitting action; 70 sometimes the floating yarns become entangled with one another so that the act of returning the proper yarn to the normal knitting position will break it off before it becomes looped onto the needles. 75

The object I have in view is to provide knitting-machines with yarn-engaging means for positively clamping or securely holding the floating yarn, or yarns, in the inactive position until it is reintroduced to 80 the needles. The thus secured yarn is neither untwisted or twisted nor acted upon in any degree between the said clamping or binding means and the yarn-carrying bobbin. In other words the yarn used (whether it be 85 heavy or light, soft or hard twisted, or strong or tender) is unaffected in any manner whatever while it is floating and positively confined in my improved device, and is reintroduced to the needles in its normal 90 condition. The means employed to effect the result just stated is equally adaptable to knitting-machines having revoluble knitting-cylinders and stationary cam-rings, or 95 stationary knitting-cylinders and revoluble cam-rings.

In the accompanying two sheets of drawings, Figure 1 is a substantially central transverse sectional view, taken on line 1 1 of Fig. 2, showing my present invention as 100 applied to a knitting-machine employing a revoluble knitting-cylinder; only the parts intimately associated or coöperating with the invention being represented, the device being shown in the closed or normal position. Fig. 2 represents a corresponding top plan, view, the needle-cylinder, needles and sinkers being omitted. Fig. 3 is a transverse sectional view taken on line 3 3 of Fig. 2. Fig. 4 is a similar view taken on line 4 4 105 of Fig. 2. Fig. 5 is an end elevation of the device showing it in the temporarily open 110

2

or elevated position to receive the inactive or floating yarn; the latter being indicated by the broken line, and Fig. 6 is a vertical sectional view, in greatly reduced scale, taken 5 on line 6 6 of Fig. 1, showing mechanism for controlling the movements of the yarn-guides or yarn-feeders, and also adapted to open or position the clamping means to receive the inactive yarn.

10 I will now first describe the illustrated elements of the knitting-machine with which my present invention is well adapted to co-operate: To the upper portion of the revolvable knitting-cylinder N is removably secured 15 the outer concentric sinker-ring n^6 , said members being constructed to receive, support and carry needles n^2 and sinkers σ in a well-known manner. The arrows represented in Figs. 1 and 2 show the direction 20 of rotation of the needle-cylinder when making circular work. A practically stationary cap-ring G surmounts the said sinker-ring; in the former is mounted a guided flat radially or endwise movable sinker-cam w having 25 an outer extension against which bears an inwardly pressing flat spring σ^1 . Contiguous to and at the right of the cylinder is located a stationary standard K, in the upper part of which a plurality of horizontally disposed fingers f^5 are pivoted; the outer ends of the latter are hooked or jointed 30 to downwardly extending wire links f^4 , each in turn being jointed to the rear end of the respective tilting-levers f^3 (see Fig. 6); the 35 front or free ends of these levers are in normal sliding contact with a corresponding rib f^2 or with the barrel proper of the drum or cylinder f secured to a cam-shaft s^1 , adapted to be rotated in a step-by-step manner 40 in the arrow direction by mechanism not shown. A pivoted manually movable latch-ring C is disposed above and concentric with the knitting-cylinder, its inner face when in use being close to the front of the upper portion 45 of the circular column of needles. Said ring has a pair of parallel lateral arms integral therewith joined together at the outer end and resting (when in the normally dropped position) on the upper end of and 50 being supported by the said standard K. The yarn-guides proper or feeders, d^1 , (three being represented) are horizontally pivoted in said arms, each being pressed by a spring d^5 . The inner or free end of each yarn-guide 55 has an eye d^4 through which a yarn is threaded. When the yarn is in the normal knitting position the corresponding guide rests upon the bottom throat-plate d^6 of the ring C; the edge of the plate being located 60 in front of and contiguous to the needles. See Fig. 1.

Referring now more particularly to the yarn-engaging device forming the subject of this invention: To the latch-ring C is secured by screws c^4 a downwardly bent arm

or bracket c^3 having its inner or free end portion extending into the chamber of the knitting-cylinder and terminating in a comparatively large flat horizontal thin plate B; the latter being located substantially even 70 with or just below the plane of said throat-plate d^6 , and having the adjacent edges of the two plates separated by a narrow annular-like space s in which the needles travel. The plate B is provided with a continuously 75 open recess s^2 formed contiguous to the side of said bracket, as clearly shown in Fig. 2. The plate is made comparatively long, see Figs. 1 and 3, so as to properly position the floating yarn thereon with respect to the 80 needles at the instant it (the yarn) is brought or dropped into knitting action; the plate positions the yarn irrespective of the direction of rotation of the cylinder. If desired the plate B may be an independent 85 member secured to the bracket in lieu of being integral with it. A suitably bent swinging clamping or binding member A, as it may be termed, of wire is disposed on the upper side of said plate, its inner end portion a being horizontally supported and movable in bearings c fixed to the bracket c^3 . As drawn, the wire is bent at right angles 90 with the part a to form the shank a^1 , then bent rearwardly and substantially parallel 95 with the part a to produce the horizontal clamping member proper, a^2 , which latter terminates in the short upwardly bent yarn-deflecting arm a^3 . An operating lever b is secured to the outer end of the said part a 100 and extends upwardly therefrom at an angle and terminates in the horizontal bar part b^2 located above and projecting in front across the said yarn-guides, the arrangement being such that whenever the latter are elevated 105 (one or more as the case may be) to throw the yarn, or yarns, out of action the corresponding guide engages said bar part and temporarily lifts the lever, thereby swinging the clamp a^2 upwardly a relative distance to freely permit the entrance thereunder of the thus elevated yarn or yarns. Fig. 5 represents the corresponding position. In order to provide means for accurately adjusting the lever, b , b^2 , with respect to the 110 yarn-guides its hub is extended laterally and slotted, thus forming ears b^1 ; a screw b^2 passing through them securing the lever in the adjusted position. A light helical spring t attached to a member of the latch-ring and to the lever b is employed for normally maintaining the clamp A in yielding frictional contact with the plate B, being the closed position, whenever the yarn-guide is 115 dropped away from the lever, see Fig. 1.

The yarn-binding member A is provided at or near the rear end of its part a^2 (with respect to the direction of rotation of the needle-cylinder) with a small laterally extending fixed bent finger e having its free

end arranged to freely enter a registering hole formed vertically in the plate B. See Figs. 1, 3 and 4. The function of this device is to prevent the knitting-yarn from passing by the finger without becoming wedged under the binder a^2 ; as for example, when the yarn last referred to is being knitted into the foot of the stocking to produce a "double-sole". As thus devised the splicing-yarn is thrown into and out of action during each course of circular knitting while the said foot portion is being produced. That is to say, this yarn when temporarily elevated by its guide to the inactive or floating position will freely enter the well-rounded continuously open throat e^2 (Fig. 3) and be arrested by said finger e ; the thus floating yarn now remains in the throat during the next half-revolution of the cylinder without breaking away from the fabric. As thus arranged the floating splicing-yarn extends, during the production of each course in which it is employed, diametrically across the needle-cylinder and is temporarily held in said throat during rotation through 180° and is then withdrawn from the throat by the continuous motion of the cylinder; the succeeding float-yarns being similarly held and guided until the double-soling operation is completed.

It is of course to be understood that during the above described knitting process the binding member A remains stationary in the normally closed position. The means represented in the drawings for opening said member A to freely permit the passage thereunder of the inactive or floating yarn when it is elevated above the normal knitting plane may be described as follows: Referring again to Fig. 6 of the drawings, the said tilting-levers f^3 (one for each yarn-guide) are arranged sidewise to one another and supported on the fixed pivot-stud u , each lever being located in the path of the corresponding ribs f^2 , substantially as before stated. It may be added here that the cam-shaft s^1 makes but one revolution during the production of the stocking or knitted unit. It is to be observed also that when the front end of any one of the levers, f^3 , bears directly upon the drum's surface the corresponding connection f^4 , finger f^5 and its yarn-guide d^1 thereby drop or place the yarn in position to be knitted into the fabric, and when the said lever bears upon the raised lugs or ribs f^2 of the drum the yarn-guide will be correspondingly elevated, thus rendering the yarn inactive. Both the said positions of the yarn-guides are represented in Figs. 1 and 2. The said movements of the yarn-guide, &c., have not thus far, however, actuated the yarn-binding device A, the latter remaining normally closed, as indicated in Fig. 1. Now, in order to open the said device to receive the inactive or

floating yarn the yarn-guide is simply quickly elevated at the proper time a short distance above its normally raised position so as to engage the underside of the bar b^3 of the operating lever b secured to the said member A and swing the latter upwardly a corresponding extent. Fig. 5 shows the thus temporarily positioned parts. At certain points in the periphery of the drum f , or on one or more of its members f^2 , corresponding with the respective places in the knitting where the yarn, or yarns, are to be thrown out of action, are positioned short slightly raised lugs x which during the rotation of shaft s^1 are adapted to pass under and contact with the free ends of the levers f^3 located in the respective circular paths, thereby causing the lever, or levers as the case may be, to instantly swing its yarn-guide upwardly to engage with and correspondingly elevate the lever b , substantially as before stated and as shown in said Fig. 5. The tendency of the revolving knitting-cylinder and of the thus elevated and inactive yarn, still connected to the work and to the bobbin, acts to draw the yarn past the rear end of the plate B and into the bottom of the continuously open space s^2 and at the same time past the finger e and under the part a^2 of the then raised member A. At the instant the lug x advances past the lever f^3 the tension of spring t depresses the binder thus firmly clamping and holding the yarn between the latter and the adjacent or upper surface of the plate, the yarn-guide meanwhile dropping back to its normal elevated position (see Fig. 1) as determined by its supporting member f^5 , link f^4 , and lever f^3 , the latter then bearing upon the corresponding rib f^2 . See also Fig. 6. When the cam-shaft in its forward movement carries the rear end of said rib past the lever the latter drops onto the barrel part f , thereby causing the yarn-guide to drop until arrested by the throat-plate d^1 and again introduce the yarn into knitting action. See Fig. 1. It is obvious that a lug x in one of the circular paths may be positioned with respect to the surface f of another or adjacent circular path so that the corresponding levers f^3 will be temporarily actuated in opposite directions in a practically simultaneous manner, thereby through the medium of the links f^4 , members f^5 , &c., causing one yarn-guide to open the binder to receive its yarn therein while at the same time the previously held floating yarn is released from the binder and reintroduced to the needles by the dropping of the other yarn-guide. In the ordinary knitting operations, however, the yarn is retained in the binder until the dropped guide is positioned upon the throat-plate and the yarn well engaged by the needles at which instant the pulling

force of the moving cylinder operates to sever or break the yarn at or near the said clamping point, and without injury to the needles or machine. Thus it is clear that even though the floating yarns extending below the binding device, or point of contact between the members a^2 and B, become unduly twisted or untwisted or even reduced to a sliver condition and broken say just at the rear of the yarn-engaging part of the device the same yarn is unaffected in any manner whatever from the said contact point to the bobbin and is reintroduced to the needles in its normal condition, as before stated. In other words, any means that may produce during the knitting operation an abnormal condition or injurious effect upon the floating yarn extending below the binding device will positively not extend to and affect the portion of the same yarn confined therein and extending to the corresponding yarn-guide and bobbin.

In a knitting-machine constructed and arranged for automatically producing half-hose my present invention is well adapted to simultaneously receive and securely hold the several yarns at substantially the same instant that the respective yarn-guides are elevated to the inactive position at the completion of the work, thereby automatically stripping the latter from the needles and at the same time stopping the machine. In order to thus open the binding device to receive the yarns a lug a is or may be positioned on one of the lifting-cams or ribs f^2 .

Now, as the lug passes under the corresponding lever f^3 the latter, together with its connected members and yarn-guide, swings the member A upwardly a short distance to freely receive thereunder the yarn from the last-named guide and also at the same time the other inactive yarn or yarns then positioned by the respective cams f^2 , levers f^3 and guides d^2 . At the instant the lug passes from said lever the latter drops to its cam f^2 thereby permitting the spring t to depress the binding member and firmly engage the yarns then being supported on the plate B. Now upon lifting the latch-ring C the attendant severs the work from the yarns preparatory to transferring a knitted "top" on to the needles, the free ends of the yarn still being held securely in the binding device.

By means of my invention all the yarns are automatically secured in place at the completion of the work, thereby dispensing with clips or other analogous devices heretofore employed into which the attendant had to secure the yarns before severing them from the work.

What I claim as my invention and desire to secure by United States Letters Patent, is:—

1. In an automatic knitting-machine of the

character described, the combination with the revoluble needle-carrying cylinder, and one or more suitably mounted mechanically controlled yarn-guides or feeders, of a self-closing yarn-holding device consisting of a relatively stationary base or plate member, a movable companion member normally resting upon said plate located at the back of the row of needles, and means adapted to cooperate with the yarn-guides for actuating said companion member to receive thereunder the floating or inactive yarn extending thereto from the yarn-supply and hold it in the device without changing its normal condition until the yarn is again brought into knitting action.

2. In an automatic knitting-machine of the character described, provided with a needle-carrying cylinder and movable yarn-guides, a holding device for inactive yarns, the same comprising a substantially flat horizontally disposed stationary plate member located above the needle-cylinder and at the back of the row of needles, a swinging fellow member having a portion thereof normally resting upon the plate for frictionally clamping therebetween an inactive yarn and holding it intact until the yarn is again brought into knitting action, and means co-operating with the yarn-guides for actuating the said swinging member at predetermined points in the knitting operation, for the purpose hereinbefore set forth.

3. In an automatic knitting-machine of the character described, the combination with a revoluble annular needle-carrying cylinder, and a mechanically actuated yarn-guide having its free or guide end disposed with relation to the needles, of a stationary plate member located immediately above said cylinder, a movable fellow member having a portion thereof adapted to normally rest upon said plate, and a self-dropping arm integral with said fellow member having its free end portion extending forward over the yarn-guide, all constructed and arranged whereby the yarn-guide when actuated to throw its yarn out of action engages said arm and at the same time causes its other member to move upward from the plate so as to receive the then inactive yarn between them.

4. In an automatic knitting-machine of the character described, the combination with yarn-carrying guides or feeders, and means for actuating them so as to place the yarns in the operative and normally inoperative positions, of a self-closing yarn-binding device consisting of a suitably mounted substantially flat stationary plate, a swinging fellow clamping member having an operating arm disposed with relation to said yarn-guides, and means for imparting to the latter, whenever the floating yarn or yarns are to be held in the device, a move-

- ment in excess of that given to the guides in placing the yarn in said normal inoperative position so as to open the device and permit the yarn to freely enter therein.
5. In an automatic knitting-machine of the character described, a binding device for inactive yarns, the same comprising a suitably mounted bottom member for supporting the floating yarns, a coöperating fellow member having a portion thereof normally engaging said bottom member, means for actuating the device at predetermined points in the knitting operation so as to receive the inactive yarn and securely hold it between said members, and means associated with the device for temporarily positioning and supporting a floating splicing yarn thereon while the device remains in the normally closed position.
10. In an automatic knitting-machine of the character described, the combination with a manually controlled pivotally mounted latch-ring, yarn-guides or feeders pivoted in and bodily movable with said ring, and means for actuating the guides at predetermined points in the knitting operation for placing the yarns in the operative and inoperative positions, of a yarn-binding device secured to and bodily movable with the latch-ring, said device comprising a suitably disposed lower member adapted to support the inactive yarn, a clamping member coöperating with the lower member arranged when in use to bear directly upon the thus supported yarn and securely hold it between said members, and an operating arm secured to the clamping member having its lifting or opening movements controlled by the yarn-guides.
15. In an automatic circular knitting-machine, the combination with the needle-carrying cylinder, means for feeding a yarn to the needles, and a base member located at the rear of the needles and above the top of the said cylinder having a continuously open recess arranged to receive a floating yarn, of a companion member normally resting upon said base member adapted when in use to form a device for holding the floating yarn therebetween, and means
- coöperating with the yarn-feeding means for actuating said device so as to permit the floating yarn to freely enter therein and also to release it therefrom.
8. In an automatic circular knitting-machine, the combination with the needle-carrying cylinder, a pivotally mounted latch-ring arranged to swing above the cylinder, means carried by and movable with the latch-ring for feeding a yarn to said cylinder, and a base member located at the rear of the needles secured to and movable bodily with the latch-ring, of a companion member normally engaging said base member adapted when in use to form a device for holding the floating yarn therebetween, and means coöperating with the yarn-feeding means for actuating said device so as to permit the floating yarn to freely enter therein and also to release it therefrom.
10. In an automatic circular knitting-machine, the combination with the needle-carrying cylinder, a yarn-carrier or feeder, means for actuating the latter so as to place its yarn in the normal operative and normal inoperative positions with respect to the needles, and means for imparting to the yarn-carrier at certain predetermined points in the knitting operation a movement upward exceeding that required to place the yarn in said normal inoperative position, in combination with a yarn-clamping device including in its construction a stationary plate or base member and a fellow movable member normally resting thereon and located at the back of the needles, means for actuating the said movable member of the device so as to receive therein and also to release therefrom the floating or inactive yarn, and a latch-ring or movable member having both the said yarn-clamping device and the yarn-carrier support or mounting secured thereto whereby they are adapted to be bodily movable simultaneously.
15. Signed at Providence, R. I., this 21st day of May, 1908.
